Primary Examiner — Marie D. Fast Horse

(57) **CLAIM**

The ornamental design for a desk phone expansion module,
as shown and described.

DESCRIPTION

This application is filed concurrently with the U.S. design
application Ser. No. 29/738,375 and entitled "Desk Phone

and Portion(s) Thereof" by Bowman WANG et al., which is
herein incorporated by reference in its entirety.

This application is filed concurrently with the U.S. design
application Ser. No. 29/738,376 and entitled "Desk Phone
and Portion(s) Thereof" by Bowman WANG et al., which is
herein incorporated by reference in its entirety.

This application is filed concurrently with the U.S. design
application Ser. No. 29/738,377 and entitled "Desk Phone
and Portion(s) Thereof" by Bowman WANG et al., which is
herein incorporated by reference in its entirety.

FIG. 1 is a front-left perspective view of a first embodiment
of a desk phone expansion module, showing our new design;
FIG. 2 is a top-right-back perspective view thereof;
FIG. 3 is a bottom view thereof;
FIG. 4 is a top view thereof;
FIG. 5 is a left-side view thereof;
FIG. 6 is a right-side view thereof;
FIG. 7 is a front view thereof;
FIG. 8 is a back view thereof;

FIG. 9 is a front-right view thereof in an in-use position,
being connected to a desk phone depicted in broken lines;
FIG. 10 is a front-left perspective view of a portion of a desk
phone expansion module, showing a second embodiment of
our new design in which the screen and buttons visible from
the top view of the desk phone expansion module are
depicted in broken lines;

FIG. 11 is a top-right-back perspective view thereof;

FIG. 12 is a bottom view thereof;

FIG. 13 is a top view thereof;

FIG. 14 is a left-side view thereof;

FIG. 15 is a right-side view thereof;

FIG. 16 is a front view thereof;

FIG. 17 is a back view thereof; and,

FIG. 18 is a front-right view thereof in an in-use position,
being connected to a desk phone depicted in broken lines.
The broken lines in FIGS. 9 and 18 showing the connected
desk phone depict environmental subject matter only and
form no part of the claim, while all other broken lines depict
portions of the desk phone expansion module that form no
part of the claimed design.

The thin, black lines shown in long dashes with intermittent
breaks are shading and/or tangent lines to show contour of

(Continued)

the surfaces or curved edges of a desk phone expansion module, and do not actually appear on the surface of the device.
